(57) **CLAIM**

The ornamental design for a bottle, as shown and described.

DESCRIPTION

FIG. 1 is a perspective view of a bottle showing the claimed design;

FIG. 2 is a side plan view thereof;

FIG. 3 is a front view thereof;

FIG. 4 is a top plan view thereof; and,

FIG. 5 is a bottom view thereof.

The broken lines illustrate portions of the bottle that form no part of the claimed design.
